IMPACTING TOOL

Edward B. George, Chicago, Ill.

Application January 22, 1940, Serial No. 314,909

2 Claims. (Cl. 60—62.5)

This invention relates in general to impacting tools adapted for delivering blows in rapid succession. Tools of this type in various sizes and equipped with different types of operating tool elements or implements are capable of employment for riveting, drilling, hammering, metal straightening and smoothing, and for various other purposes.

As an exemplification of one tool of this general character in which the principles of my invention may be embodied, I have here shown for illustrative purposes a metal straightening and smoothing tool adapted for straightening and smoothing automobile fenders, bodies, and other sheet metal objects. It will be obvious, however, that the principles of my invention are equally applicable to impacting tools designed or adapted for various purposes.

Many tools of the character indicated are of the pneumatic type operated by compressed air, but the use of such tools involves expensive air compressing equipment and flexible hose from the compressed air supply to the tool. Electrically operated tools for these purposes have also been used to a limited extent, but the excessive vibration of the tool as a whole inherent in the mechanical operation of the impacting element is very tiring to the operator and results in rapid wear and disintegration of the tool parts.

One of the primary purposes of my present invention is to provide an electrically or mechanically operated tool which will be light in weight and easily handleable, but in the operation of which the vibration will be reduced to a minimum, thus making the tool easy to handle, less tiring to the operator, and contributing to the longevity of the device.

With these ends in view, my invention contemplates the provision of a tool in which a pneumatic vibration-absorbing, motion-transmitting means is interposed between the mechanical power transmitting member and the impacting implement so that the requisite reciprocatory movements are imparted to the impacting implement without the production in, or the transmission to, the tool as a whole of the excessive vibration which, for the reasons above indicated, is highly objectionable in tools of this character.

Referring for a better understanding of the invention to the exemplification thereof illustrated in the drawing,

Fig. 1 is an elevation partially in section of a tool embodying the principles of my invention;

Fig. 2 is a fragmentary sectional view on the line 2—2 of Fig. 1; and

Fig. 3 is a sectional view of another form of impacting implement.

Referring to the drawing more in detail, reference character 5 indicates generally the body or shell of the tool of cast metal, generally cylindrical in shape and opening laterally near its upper end to accommodate the head 6 of a motor carrying member which is secured to the body 5 by a series of bolts or screws 7, its proper position with respect to the body being insured by one or more dowel pins 8.

An electric motor 9 is carried by the head 6, the motor shaft being equipped with a pinion 11 meshing with and adapted to operate an internal gear 12 carried by a shaft 13 which is journaled at one end in a bearing 14 seated in a suitably formed support 15 on the interior of the body 5, and journaled at its other end in a bearing 16 seated in the head 6. While the shaft 13 may, if preferred, be a continuation of the motor shaft, I have found that the most efficient operation is attained with the use of the reduction gearing shown, which permits the employment of a high speed motor.

The shaft 13 carries intermediate its ends an eccentric 17 surrounded by a head 18 at the upper end of the reciprocatory rod 19, which is the operating member of the mechanism. For friction reduction, roller or ball bearings 21 are interposed between the eccentric 17 and the head 18.

To the lower end of the body 5 there is securely attached by means of stud bolts 22 a tapered housing 23 and a cylindrical element 24 interposed between the housing and the body and rigidly connected to both. A diaphragm 25 of suitably strong and flexible material, such for instance as a laminated, rubber-impregnated fabric is interposed between the member 25 and the body 5 where it is securely clamped at its peripheral margin between the annular shoulder 26 formed on the body 5 and an opposed shoulder 27 formed at the upper end of member 24. One or both of these shoulders is provided on its face with indentations in which the material of the diaphragm is compressed when the bolts 22 are tightened up to thereby securely clamp the diaphragm in position and insure a hermetic seal around the diaphragm.

A similar diaphragm 29 is clamped between the shoulder 31 at the lower end of member 24 and a shoulder 32 at the upper end of the housing 23 so that an air tight compartment having flexible upper and lower walls is provided between the diaphragms 25 and 29.

The upper diaphragm 25 is secured at its center to the lower end of the rod 19 by a bolt 33. To afford protection to the diaphragm against abrasion and wear during its operative movements, spheroidal clamping washers 34 and 35 are interposed respectively between the upper face of the diaphragm and the end of the rod 19 and the lower face of the diaphragm and the head of the bolt 33. Similarly, the lower diaphragm 29 is connected by a bolt 36 and washers 37 and 38 with the upper end of a plunger 39 arranged for reciprocatory movement in the tapered guide 41 forming a downward extension of the housing 23. In the lower end of this guide is disposed the impacting tool or implement 42 adapted to deliver to the material or object being worked the blow transmitted to it from the plunger 39. To prevent the impacting implement from dropping out of the lower end of the guide, it is provided with a circumferential groove 43 in which is seated a circular expansion spring 44 adapted to engage the wall of the guide bore with sufficient friction to retain the implement 42 against accidental displacement.

When the tool is to be employed as a sheet metal straightener or smoother, an anvil between which and the implement 42, in this instance in the form of a hammer, the work is interposed, is provided as a part of or an attachment to the tool. As illustrated, the anvil in this instance assumes the form of a roll 45 rotatably supported so as to freely caster upon a ball 46 at the bottom of a bore formed in the upturned end of an arm 47 which is pivoted at 48 on a bracket 49 secured to and projecting from a stationary part of the tool, such for instance as the cylindrical member 24. The anvil is maintained in the operative relation to the hammer illustrated in the drawing by means of a link 51, the upper end of which is attached to a bell crank shaped handle 52 pivoted on the bracket 49 at 53. When the handle is swung in a counter-clockwise direction about its pivot viewing Fig. 1, the arm 47 is lowered to retract the anvil 45 from the hammer 42 a sufficient distance to permit the introduction of the sheet metal work to be operated upon between them. When the work has been positioned, the handle 52 is swung back to the position shown in the drawing, whereupon in operation the tool and the anvil are traversed over the area to be worked.

The tool which is relatively light in weight may be carried and moved about by the operator who grasps the handle 54 attached to the housing 5 and to the motor 9, the handle being preferably equipped with a switch 55 by which the current supplied to the motor by the feed wires 56 may be turned on or off as desired. Although not essential to the operation of a tool embodying my invention, a light coiled spring 57 may be interposed between the diaphragms 25 and 29 and anchored at its ends in the head of bolts 33 and 36. This spring performs the dual function of insuring against the loosening of the bolts and serves to cushion the upward movement of diaphragm 29 so as to relieve to some extent the strain upon the diaphragm induced by vacuumatic action during the operation of the tool.

The hammer 42 illustrated in Fig. 1 has a flat or a convex face for cooperative action with the anvil 45. In Fig. 3, however, I have shown a hammer which is particularly adapted for rivet-

ing purposes, and in this instance, the convex face of the hammer head is provided centrally with a depression 58 adapted to receive and form into a convex head the end of the rivet to be swaged.

A tool constructed in accordance with my invention operates in the following manner:

The operating member 19 is reciprocated upon rotation of the shaft 13 by the motor, and on its upward movement carries with it the central portion of the upper diaphragm 25, thereby flexing the diaphragm upwardly. This diaphragm induces a partial vacuum in the chamber between the diaphragms, thereby causing the lower diaphragm 29 to flex upwardly and draw the plunger 39 upwardly in its guiding bore. Upon downward movement of the operating member 19, the diaphragm 25 is flexed in the opposite direction, and through the compression of the air in the sealed chamber flexes diaphragm 29 downwardly, thereby causing the plunger 39 to deliver a blow to the hammer 42 which is transmitted to the work. The movement of the operating member 19 is therefore pneumatically transmitted to the hammer so that the shocks, jars, and strains which would be produced by a direct connection between the member 19 and the plunger 39 are eliminated, and at the same time a sharper, snappier blow is delivered than would be possible with a direct connection.

It is believed that my invention and many of its inherent advantages will be apparent from the foregoing and that the structural details shown and described are illustrative merely and may be varied within considerable limits without departing from the essence of my invention as defined in the following claims.

I claim:

1. In an impacting tool, the combination of a main body, a shaft mounted therein, means for rotating said shaft, an elongated housing, a pneumatic unit comprising a cylindrical body and flexible end walls interposed between and fixedly connected to said main body and said housing, a spring, interposed between said flexible end walls, a reciprocatory operating rod connected to the upper one of said flexible walls and connected for reciprocation by said shaft, and a tool operating plunger connected to the other of said flexible walls and arranged to be reciprocated thereby in said housing.

2. In an impacting tool, the combination of a main body, a housing, a pneumatic unit interposed between and rigidly secured to said body and housing, said unit comprising flexible end walls and an interposed cylindrical member providing an enclosed, hermetically sealed chamber between said end walls, a spring in said chamber interposed between said flexible end walls, a shaft mounted in said main body, an operating rod connected to be reciprocated by said shaft and connected to one of said flexible walls to positively flex the same in opposite directions, and a tool operating plunger mounted to reciprocate in said housing and connected with the other of said flexible walls to be positively actuated in opposite directions by the flexation of the flexible wall to which it is connected, pneumatically induced by the positive flexation of said other flexible wall.

EDWARD B. GEORGE.
